UNITED STATES PATENT OFFICE.

HUGH MALCOLM MCCORMICK AND SARA WEBER MCCORMICK, OF MORENCI, MICHIGAN,
ASSIGNORS, BY MESNE ASSIGNMENTS, TO HUGH MALCOLM MCCORMICK, OF MO-
RENCI, MICHIGAN.

BIBELT.

Application filed December 1, 1926. Serial No. 151,904.

This invention relates to support and reduction of that portion of the human abdomen located within the pelvic cavity by means of leverage, as opposed to constriction, and is adaptable for use by both the human male and female; but its principal purpose is to provide women with adequate, comfortable and healthful abdominal support (and abdominal reduction when desired) in conditions of abdominal ptosis, and to supply the patient, surgeon and nurse with a long needed and much wanted type of abdominal supporter in post-laparotomy and post-parturition cases.

The fundamental characteristic of our invention is the transformation of an ordinary abdominal bandage or girdle into a dual garment having two distinct and separate functions; the one intra-pelvic abdominal support, the other all the common uses of abdominal bandages or girdles in general. The intra-pelvic abdominal support portion is so constructed and positioned that, when adjusted to the person, it encloses, confines, and conforms to the shape of the lower abdomen. When the diverged front ends of the levers are drawn toward each other by force the initial action is strains upon the upper portions of the bases or fulcrums of said levers, which strains are directed simultaneously frontwardly and downwardly, while every other abdominal bandage lifts, initially, upward and rearward. As the diverged front ends continue to be drawn toward each other said strains descend along the lever's bases or fulcrums until the front ends of said levers are in full operation upon the intra-pelvically located base of the abdomen. During this operation the lever's front ends have lifted until, their full force exerted, they support and uphold the base of the abdomen by a simultaneous upward and backward pressure which is at substantially right angles to the initial downward and frontward strains, and this final leverage forces the intra-pelvically located lower abdomen obliquely centerward and upward away from the groins and at the same time backward. True intra-pelvic abdominal support reinforces and assists nature by tending to restore displaced and misplaced lower abdominal organs and tissues to their normal positions. To effect the transition from a corset to an abdominal belt, which is the subject of this invention, we singly or jointly had to produce invention

after invention, as shown by our above named United States Letters Patents, to be able to finally correlate and produce our original improvement in abdominal bandage endeavor. Bi-belts constitute our matured and final contribution to intra-pelvic abdominal support and are, in our opinion, our most useful, needed and valuable abdominal supporters and reducers—the combination of two well-known and largely used things (abdominal belts and uplift belts) which, united, produce a new, useful, much needed and long wanted result.

The outer portion of bi-belts consists of a band or girdle which embraces a portion of the abdominal support, and depending from the lower edge of the girdle are hose supporters. The advantage of this arrangement is, that the elastic pull of the hose supporters does not cause a downward pull on the lower abdomen, but transmits this strain only to the outer sections of bi-belts, and does not interfere with the normal operation of the inside levers.

In designing abdominal uplift belts for corsets the measurements are taken from the waistline or zone belt line of a corset downward, as described in Patent Number 1,473,241, November 6, 1923.

In designing the inner belts or levers of bi-belts the measurements are not taken from the waistline at all but from the top of the outer girdle down, and as the top of the girdle may vary to please a particular designer, and because the height of the girdle should vary to complement figures of different types, there can be and is considerable latitude as to the distance the lower front corners of said inner belts or levers may be from the top front edge of the outer girdle. To illustrate: In designing for corsets (United States Letters Patent Number 1,473,241) the top front corners of uplift belts are approximately three inches below the natural waistline; but, for an average figure, the top front corners of the inner belts or levers of bi-belts will be approximately one and one-half inches below the top edge of the outer girdle.

Our invention is shown by way of illustration in the accompanying drawings, in which:

Fig. 1 is a plan view of the abdomen supporting belts and hose-supporting girdle; and Fig. 2 is a perspective view of a person on which the abdominal support is laced and

showing the hose-supporting girdle unfastened.

The illustrated embodiment of the invention comprises a hose-supporting girdle 1, Fig. 1, which consists of two sections A and B, which are adjustably connected by lacing 2. The upper and lower edges of the sections A and B are suitably curved so as to fit properly about the body. Attached, as by stitching 10 to the girdle, is an abdominal supporter 3, Fig. 1, which is in two sections C and D, the section C being secured by a line of stitching 4 to the girdle section A in outwardly spaced relation from the laced edge 5, and the 15 section D being secured by a line of stitching 6 to the girdle section B in outwardly spaced relation from the laced edge 7.

It is to be noted that the rear ends of the abdominal supporting sections C and D are 20 secured to the girdle by lines of stitching 4 and 6 respectively, so that said ends are disposed in upwardly diverging spaced relation to each other.

The upper edge of the abdominal supporting sections should be considerably shorter than the lower edge thereof, and this is attained by arranging the attached ends in upwardly diverging spaced relation, thereby permitting the upper edges to be shortened 30 without unduly constricting the body of the wearer.

A further object for disposing the abdominal supporting sections C and D divergently upward is that such positioning places the 35 plane of the fulcrum at more nearly a right angle to the oblique forward and downward exertion of force, thereby resulting in increased comfort and efficiency.

The abdominal supporter 3, Fig. 1, is of fabric which is relatively stiff, but flexible, and it will be observed that the upper ends of attachment to the girdle are considerably above the lower abdominal region, are at about the waist line. The ends of the sections of the 45 abdominal supporter which are connected to the girdle, are relatively wide and the lower edges of each section curve upwardly and downwardly to fit snugly over the thigh. The front edge of each section diverges downwardly to follow and conform to the downward and inward receding curve of the lower abdomen. As shown in Fig. 2, the front edges of the sections C and D of the abdominal supporter are provided with ductile emphasis plates m, Fig. 1 to reinforce their 55 lower front corners, and with hooks to permit the sections to be laced together.

When bi-belts are applied to the person, the lacing 8, Fig. 2, is commenced from the top 60 and as the downward diverged front edges are drawn together, a diagonal pull is effected which acts from the upper parts of attachment of the supporter sections to the back of the girdle, downward and frontward. The 65 exertion of force at the free front ends of the

supporter sections finally provides a lifting action at substantially right angles to the initial downward and frontward pull, and this lifting action subjects the lower abdomen and its intra-pelvically situated contents to an 70 oblique centerward, upward and rearward lift and support.

It will be observed that the girdle section B, Fig. 1, is considerably longer than the section A. This construction permits the girdle 75 to be fastened on either the right or left side as preferred, suitable fastening devices being employed for this purpose. The girdle 1, Fig. 1, is considerably wider than the abdominal support. Attached to the lower edge of 80 the girdle at proper intervals, hose supporters 9, attached to reinforcements k, are provided for each stocking. By this construction and arrangement the elastic pull exerted by the hose supporters 9 is transmitted to the 85 outer girdle only so that no harmful effect can be experienced by downpull upon the abdomen.

The functions of the outer open and extended sections A and B, shown in Fig. 2 are 90 to provide a base for hose-supporters and to ensure a better contour of the front of the figure below the fullest part of the abdomen. As far as the operation of the levering uplift belts is concerned, sections A and B, front- 95 ward from stitching lines 4 and 6, Fig. 1, can be dispensed with altogether, since the uplift belt portions C and D, Fig. 2, are wholly free from and act independently of said portions of sections A and B; but, when this is done, 100 the upper front ends of uplift belts should be designed high enough to properly contain the upper portion of the abdomen.

From the above, the outstanding advantages of this invention will be appreciated. 105 Bi-belts have the dual function of providing an efficient abdominal lifting and supporting device, and a hose supporting girdle which eliminates harmful downpull upon the abdomen. This garment gives the wearer absolute freedom of movement without sacrificing the abdominal support so necessary for many women.

While we have described our bi-belts in more or less detail to comply with the requirements of the statute, it is nevertheless desired that this detailed description be considered merely as illustrative and not as limiting, and it is to be understood that changes and modifications may be made by those who become skilled in this art without departing from the invention as defined in the following claim.

What we claim as new and desire to secure by Letters Patent is:

A bi-belt comprising a girdle, a pair of opposed abdominal supporting members having their rear ends attached to said girdle, said attached ends of the supporting members being disposed spaced from each other, means 130

for connecting the front ends of the supporting members and means for connecting the free ends of the girdle, the rear ends of the supporting members diverging upwardly and
5 the front ends of said supporting members diverging downwardly whereby as the downwardly diverged front ends continue to be drawn toward each other same exert a simul-

taneous upward and backward pressure at substantially right angles to the direction of 10 the initial strains.

In testimony whereof we have hereunto signed our names to this specification.

HUGH MALCOLM McCORMICK.
SARA WEBER McCORMICK.
